UNITED STATES PATENT OFFICE

WALTON L. HAMPTON, OF LOUISVILLE, KENTUCKY, AND VERN A. TRACY, OF SALT LAKE CITY, UTAH

LABEL-PASTING DEVICE

Application filed May 12, 1928. Serial No. 277,215.

The invention relates to improvements in devices for applying paste to labels, or the like, and has for its object the provision of an improved device of this character which is of simple construction and highly efficient in use.

Another object of the invention is the provision of a simple and efficient device of this character which may be mounted on any ordinary table and operated efficiently for the application of paste to labels, or the like.

Another object of the invention is the provision of a device of this character which is capable of economical manufacture.

Other objects will appear hereinafter.

15 The invention will be best understood by reference to the accompanying drawings forming a part of this specification, and in which

Fig. 1 is a top plan view of a device embodying the invention.

Fig. 2, an elevation of the same, and

Fig. 3, a section taken substantially on line 3—3 of Fig. 2.

The preferred form of construction illustrated in the drawings comprises a paste trough 5 substantially V-shaped in cross-section, and provided at the bottom with a slot 6 for the escape of paste therefrom.

The trough 5 is provided at each end with 30 a guide lug or ear 7, adapted and arranged to run in a guide slot 8 in a corresponding bracket or standard 9. Each of the brackets 9 is provided at its bottom with a perforated foot or flange 10, by means of which the same 35 may be secured to a table top 11, as indicated.

In use a stack of labels 12 is placed upon the table 11 between the standards 9, with the trough 5 resting thereon adjacent to the end thereof to which it is desired to apply 40 the paste. The trough 5 is then filled with the paste, which is of semi-solid consistency so that it will pass automatically by gravity downwardly through the slot 6 on to the edge of the uppermost label 12. The labels 12 are 45 then withdrawn successively from the top

of the stack, and each label edge will receive its due supply of paste. Where the stack of labels is narrower than the length of the trough 5, strips of paper 13, or the like, are arranged in the trough 5 at each end thereof to close the ends of the slot 6 where the length 50 of said slot exceeds the width of the stack of labels as shown.

It is also obvious that the length of the paste trough 5 may be made equal to the width of the labels in which case no strips 13 would be necessary, but, of course, a special trough 55 will have to be provided for each size of labels treated.

By this arrangement the device may be 60 readily adapted to use in conjunction with labels of various sizes, and a simple and effective device is provided for quickly and efficiently applying paste to the edges of labels. Obviously by properly arranging the 65 stack of labels 12, a strip of paste of varying width may be applied to the labels.

While we have illustrated and described the preferred form of construction for carrying our invention into effect, this is capable 70 of variation and modification without departing from the spirit of the invention. We therefore do not wish to be limited to the precise details disclosed, but desire to avail ourselves of such variations and modifications as fall within the scope of the appended 75 claims.

Having thus described our invention, what we claim as new and desire to secure by Letters Patent is:

1. A device of the class described comprising a paste receptacle mounted for free vertical movement and arranged to rest on a pile of labels or the like, said receptacle being provided at its bottom with an open slot forming an escape for paste; and a sealing member in the form of a flexible strip laid in one end of said receptacle and conforming to the walls of the same and closing 80 one end of said slot.

2. A device of the class described comprising 85

ing a paste receptacle mounted for free vertical movement and arranged to rest on a pile of labels or the like, said receptacle being provided at its bottom with an open slot forming an escape for paste; and two sealing members in the form of strips of paper arranged at each end of said receptacle conforming to the walls thereof and sealing each end of said slot.

In witness whereof, we have hereunto set
10 our hands this 3rd day of May, 1928, and this
7th day of May, 1928.

WALTON L. HAMPTON.

VERN A. TRACY.
